UNITED STATES PATENT OFFICE.

WILLIAM C. STEWART, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

SORTING MACHINE.

Application filed January 3, 1922. Serial No. 526,608.

This invention relates to machines for sorting blanks in accordance with a selected characteristic of the blanks.

The present practice in shoe factories in the matter of sorting block soles often results, because of inefficiency and carelessness in sorting, in very considerable waste through the use of soles which are longer than needed for the particular size or style of shoe in process of manufacture. With proper sorting and distribution of the soles in magazines or other receptacles it is obvious that the conditions are such as to facilitate economical use of shoe bottoming material.

It is an object of the invention to provide an improved machine of the class specified which will sort blanks in accordance with variations in a given dimensional characteristic. While the invention is disclosed for the purposes of illustration in a machine for sorting shoe soles, it will be understood that the invention in its entirety and various important features thereof may have other applications and uses.

In the illustrative machine, there is provided a plurality of means for caliperizing blanks along a length dimension thereof, as they pass along a support, arranged to control the discharge of the blanks in accordance with the determinations of the caliperizing means, the discharging means being operated by the blanks as they are caliperized. Conveniently the caliperizing means comprises a plurality of gages movable over the support to control latching means for trap doors in the support.

In a practical form of the invention, there is provided a series of stamps each adapted to stamp a blank having a given dimension, in an organization in which only those blanks which correspond to the mark carried by a given stamp are delivered in operative position with respect to that stamp.

As shown, the blanks are moved through the stock treating means of the machine by mechanism which moves the blanks along a rectilinear path. Conveniently, this feeding mechanism comprises a reciprocable member having movable gravity-operated fingers which successively engage the individual blanks to propel them along the support.

The above and also other features of the

invention, residing in the general organization of the machine for the purposes in view, together with certain details of construction and combinations of parts, will now be described with reference to the accompanying drawings and pointed out in the appended claims.

In the drawings:

Figs. 1 and 2 together disclose a plan view of a machine showing one embodiment of the invention;

Figs. 3 and 4 together show the machine in side elevation;

Fig. 5 is a front view of the machine; and

Figs. 6 and 7 disclose details of the mechanism for feeding the blanks along the blank supporting surfaces of the machine.

In the illustrative machine there is provided a supporting table 8 upon which the blanks are placed by the operator, preferably in contact with pins 10 which extend upwardly from feed slides 12 set in guideways in the table 8. As shown the slides 12 have their upper surfaces in the same plane as the supporting surface of the table and each is provided with a plurality of holes 14 adapted to receive selectively the pins 10. It will be understood that the pins serve also as gages for the proper positioning of the work in accordance with the variations in the size of the blank material to be fed through reciprocations of the slides 12. Mounted for rocking movement in the frame of the machine near the front end thereof is a shaft 16 to which is rigidly connected a pair of arms 18 connected to the slides 12 by means of relatively short links 20. Fixedly attached to one end of the shaft 16 is a downwardly extending arm 22 to which is pivoted a bar or rod 24 (Fig. 3) extending the full length of the machine and pivotally connected at its other end to the upper end of an arm 26 which is in turn rigidly secured to a rocking shaft 28 (Fig. 4). It will be clear that upon oscillation of the shaft 28 the shaft 16 will be rocked to cause reciprocation of the slides 12, the construction being such that the blanks in the path of the pins 10 will be carried to the left in Figs. 1 and 3 to place the blank with its forward edge closely adjacent to the edge 30 of the table 8 and thus in position to be operated upon by a second feeding means

designed to progress a series of blanks intermittently along a support made up of a

plurality of trap doors 32. As shown the doors 32 are each pivoted to side bars 34 of the machine frame by means of hinge pins 36 so positioned that the doors turn or swing 5 about a line parallel with the longitudinal axis of the door. It will be understood that the doors are locked in blank supporting position and released at the proper time to discharge the blanks after each blank has 10 been properly tested as to a given dimension so that it may be piled with other blanks having the same dimensional characteristics.

For feeding the blanks along the series of 15 trap doors there is provided a feeding mechanism which, in the illustrative machine, is shown to comprise a pair of bars 40 (Figs. 1 and 2) mounted for sliding movement in the cross brackets 42 secured 20 fixedly on the frame of the machine. Each bar 40 carries at regularly spaced intervals a plurality of feed pawls 44 pivoted to the bar and gravity-operated so that the lower end of each pawl extends into the path of 25 the blanks. Upon inspection of Figs. 6 and 7 the mode of operation of the pawls will be readily understood, it being evident that the pawls turn about their pivot points to ride over the blanks upon movement toward 30 the front of the machine and that upon movement in the reverse direction the pawls engage each with the front edge of a blank and serve to move it rearwardly, a block 46 being fixedly secured to its corresponding bar 40 and operative 35 to hold the adjacent pawl in its vertical blank feeding position. It will be understood that the whole series of blanks are fed intermittently along over trap doors 32, each 40 step of the feeding movement corresponding in extent closely to the transverse dimension of the trap doors whereby each blank is successively positioned over a number of 45 trap doors until it reaches the proper one where it is ejected. Pivotal secured to the rear end of each bar 40 is a pair of links 50 in turn pivoted at their ends to the upper end of a lever arm 52 carried fixedly on the 50 rocking shaft 28, the arrangement being such that the oscillatory movement of the shaft 28 causes reciprocation of the feed bars 40 to effect feeding of the blanks as above described.

Extending lengthwise of the machine is 55 a supporting bracket 60 bolted at its ends to the brackets 42, the said longitudinal bracket serving to support a plurality of latch operating devices, there being preferably one for each trap door. Inasmuch as 60 all of the latch operating devices are of like construction it is sufficient that one be described, as shown in Fig. 1 of the drawings. It will be understood that the latch referred to is the pivot member 62 (Fig. 65 5) which is adapted to turn about a pivot pin 64 supported in a bracket 66 extending upwardly from the side bar 34 of the machine frame. In the illustrative construction the lower end of the latch 62 is provided with a projection which 70 seats itself in a small cup-shaped cavity in the adjacent end surface of the trap door 32 at a point closely adjacent to the longitudinal edge of the trap door opposite to that which is adjacent the hinge 75 pins or pivots 36. It will be understood that when the latch is swung outwardly, that is toward the right in Fig. 5, about its pivot 64, the trap door 32 will drop downwardly about its pivots 36 and thus discharge the 80 blank which was resting on the door. Slidably mounted on a rod 68 fixed to the bracket 60 is a plate 70 provided with a plurality of openings 72 for receiving selectively a gage pin 74 which projects downwardly almost into contact with the trap door 32 and thus into the plane of the blank resting on the trap door. As shown, the plate 70 has an extension 78 provided with a bore through which passes the bolt 80 85 also fixed in the bracket 60, a spring 82 being arranged to surround the bolt between the extension 78 and the head of the bolt, the spring serving to retain the sliding plate 70 in its normal operative position. It 90 will be understood that if the blank B resting on the trap door 32 be forced to the right in Fig. 5 it will, if long enough, contact with the lower end of the pin 74 and shove it along carrying the plate 70 with it 100 in the same direction and through the pivotal connection 90 between the plate and the latch 62 will force the latch to the right (Fig. 5) swinging it about its pivot point 105 at 64 and causing the release of the trap door in a manner that will be readily understood from the foregoing description.

In order to test the blanks with respect to the longitudinal dimension of each so that 110 blanks of a given length may be deposited in one stack or magazine and blanks of other given lengths in corresponding stacks or magazines there is provided a plurality of gages 100, 102, 104, 106, as disclosed most clearly in Fig. 1 of the drawings, the number provided being variable in accordance with the requirements of the work. As shown, the gages are mounted upon a frame or other supporting member 110 (Figs. 1 and 115 5) and, in the illustrative construction, each gage comprises a plate 112 slidable in the support 110 and having a portion arranged to extend downwardly at right angles to the plate to serve as the gage. For this reason the end of each gage extends almost into contact with its corresponding trap door located just below and hence upon moving the gage to the right in Fig. 5, it will contact with the blank which at that time is resting 120 on the door. The other end of the plate 112 125 130

has a portion 114 which extends upwardly at a right angle to the body of the plate and has passing therethrough an adjusting member 116 provided with a collar secured to the adjusting member at each side of the extension 114, the adjusting member having further a portion which is screw-threaded into the supporting bar 110. It will be obvious that upon turning the adjusting member 116 the plate 112 and thus the gage 100 will be moved from right to left or in the reverse direction in Fig. 5. It will be understood that the adjusting mechanism for all the gages may be of the same type as that described for the gage 100. For operating the supporting bar 110 slideable along its supporting rods 120 (Figs. 1 and 2) at each end of the machine there is provided a U-shaped frame 122 (Figs. 3, 4 and 5) which is pivoted at each end upon pivots 124, 125 supported in brackets in the frame of the machine, the said U-shaped frame comprising arms 126 near each end, which arms are pivotally connected at their upper ends by means of links 128 to the supporting bar 110. For operating the frame there is provided adjacent the pivot 125 therefor an arm 132 rigid with the frame and having its upper end bifurcated as shown at 134 (Fig. 4) to receive one end of a link 136 which connects the arm 132 with a bell crank lever 138 pivoted at 140 (Fig. 5) on the frame of the machine and having a roll 142 which rides upon the cam surface 144 of the barrel cam 146, the arrangement being such that as the bell crank lever 138 is rocked, the frame 126 will be oscillated about its pivots 124, 125 and thus cause reciprocations of the supporting bar 110 upon which are mounted the gages 100, 102, 104 and 106. It will be understood that the operative movement of the gages, that is, the movement toward the right in Fig. 5, will take place immediately after a feeding operation by the feed bars 40 which operate to position a whole series of blanks upon the trap doors. Referring again to the blank B (Fig. 1) the gage 100 will be moved to contact with the end of the blank and, if it be of a certain length, it will be forced against the pin 74 adjacent the other end of the blank door, in which case the door will be unlatched, thus permitting the blank to drop toward the magazine below. If, however, the blank is not long enough to cause actuation of the pin 74 and slide plate 70, the trap door of course will remain latched in its blank supporting position. Similarly, the other blanks will be tested by the movement of their corresponding gages 102, 104, 106 toward corresponding pins 74 supported by other slide plates like that shown at 70 in Fig. 1. Certain of the blanks will be long enough to actuate the pins and thus release the latch to permit dropping of the trap doors upon which the blanks rest. Immediately following this operation, the trap doors which were released are automatically relatched in the operation of the machine. Following this a new feeding movement of the feed bars 40 takes place by which the blanks still supported on the trap doors are moved one step to the left in Figs. 1 and 2 and a new blank introduced from the table 8. These operations are repeated and in this way the blanks are segregated and deposited in their respective magazines. In the illustrative construction the shortest gage is at the first station, that is, opposite the blank B in Fig. 1 and thus the construction is such that the longest blank of those being operated on in the machine, will be deposited in the magazine below the first trap door, it being possible to ensure such disposition of the blank by proper adjustment of the gage 100. It will be understood that a blank which is not long enough to operate the pin 74 when it is opposite the gage 100 will pass to the next trap door and to each in turn until it does reach a trap door where the gage and pin together with the blank co-operate to release the latch permitting the trap door to drop, thus depositing the blank in its proper magazine.

Means is preferably provided for automatically returning the trap doors to latched position, the said means being operated in properly timed relation to the other mechanisms and immediately following the operative movement of the gage supporting bar 110. As shown, each trap door 32 is provided with an arm 150 extending upwardly from the trap door adjacent to its pivot line at one end thereof (Figs. 1, 3 and 4), the upper end of each arm carrying a pin 152 which extends laterally from the arm and into the path of movement of a projection 154 on a reciprocable bar 156 slideable in a guideway provided by brackets, one of which is shown at 158 (Fig. 5 of the drawings). At the rear end of the machine the bar 156 has pivoted thereto a link 158 which is in turn pivoted to the upper end of a lever 160 (Figs. 2 and 4) carried by a sleeve 162 fixed upon the rocking shaft 28. In case it is desired that the blanks be stamped or otherwise marked for identification purposes, this can conveniently be done before they are deposited in their respective magazines. While the illustrative machine provides marking means for the blanks it will be understood that such means or mechanism may be omitted if desired. As shown in the illustrative machine, a support is provided for each blank, after it leaves the trap door 32, upon which it rests during the stamping operation. In each compartment 170 beneath the trap doors there is provided a plate 172 (Fig. 3) pivoted at 174 in the frame of the machine and extending practically across the compartment.

- ment to serve as a movable bottom therefor. Upon this plate the blank drops and rests during the stamping operation. Rigidly connected to each pivot 174 is an arm 176 which extends downwardly and is pivotally connected at its lower end to a bar 178 extending longitudinally of the machine. Upon reciprocation of the bar 178 the supporting plates or bottoms 172 are simultaneously operated to swing downwardly and thus discharge the blanks into the magazines 180 located below. Immediately thereafter the bar 178 is moved in the opposite direction to return the bottoms 172 to blank supporting position. In the construction shown, operation of the bar 178 is provided for by pivotal connection with a lever arm 184 extending downwardly from the rocking shaft 28.
- Conveniently, the marking means for placing identifying marks upon the blanks comprises a plurality of stamping members 190 (Fig. 3) which are preferably circular members carried at the upper ends of rods 192 adjustable rotatably in sleeve members 194 carried by hubs 196 secured fixedly to the shaft 198, the latter being mounted in brackets 200 at both front and rear ends of the machine. Pinned to the rear end of the shaft adjacent the bracket 200 is a lever arm 202 to the upper end of which is pivotally connected a link 204 (Fig. 5) preferably adjustable as to length and secured pivotally at its other end to a lever 206 mounted on a pivot 208 on the machine frame and carrying a roll 210 at its free end. As shown, the roll is maintained in contact with the cam surface 212 on the barrel cam 146 through the action of the spring 214. During rotation of the cam 212 the roll 210 rides up on a high part of the cam and at the proper time drops off the high part to the low part of the cam at the point 216 and when this takes place the shaft 198 is rotated through approximately 90 degrees to bring the stamp on the circular head 190 down upon the blank with an impact that ensures the stamping of the identifying mark upon the blank. As shown, the spring 214 is secured to the rod 204 through a collar 220 which is preferably adjusted on the rod 204 so that the tension of the spring may be easily adjusted and thus proper connection with the extensible rod 204 make it possible to ensure proper stamping of the blanks as the latter rest upon the supporting plates 172. As before stated, the stamps or stamping heads 190 are circular and each carries a number of characters, such as letters or figures or other identifying marks, and are arranged to be turned so that the operator can make selection as to the identifying mark for any particular blank and magazine. In order to facilitate selection by the operator, the same identifying marks found on the stamp-
- ing head 190 are also placed on the circular member 224 and in the same order, (Fig. 3) the whole series of marks being shifted 180 degrees around the circumference of the circular member 224 as compared with the location of the same series on the circular head 190, so that the mark appearing at the front on the member 224 appears directly opposite on the head 190 where it is in a position to strike the blank when the head is moved downwardly upon the blank through the rotation of the shaft 198. Hence to secure the proper identifying mark it is necessary only to rotate the member 224 which is connected through the rod 192 with the head 190 in a manner that will be well understood.
- For applying ink or other similar substance to the edge of the head 190 and more particularly for applying it to the identifying mark which is at the time in use, there is provided a plurality of pads one adjacent each head 190. Since each pad 228 (Fig. 3) is similarly mounted and operated the description of one will serve for all. As shown, each pad is mounted on a lever arm 230 (Figs. 1 and 3) fixedly secured to a short shaft 232 rotatably mounted in a bracket 234 secured upon the side bar of the machine frame, the arrangement being such that each pad swings toward and from its corresponding head 190 of the marking means to apply the inking material to that mark on the head which will contact with the blanks during the operation of the marking means. As shown, the operating means for the pad comprises a link 236 pivoted to a projecting portion on the lever arm 230 at one end and at its other end to a bar 238 extending along the side of the machine over all of the marking mechanisms. For reciprocating the bar 238 there is pivoted adjacent one end of the machine on a bracket 242 (Fig. 2) a bell crank 244 having one of its ends 246 pivotally engaged with one end of the bar 238 while the other end of the bell crank 244 is pivoted to a block 248 in turn pivoted in the bifurcated portion 250 of a rod 252 (Figs. 2 and 5). Conveniently the other end of the rod 252 is pivoted to the upper end of the bell crank lever 138 operated from the cam 144 as above described. It will be understood that the rod 238 is reciprocated to cause application of the ink pad to the marking heads 190 while the latter are in their upper position of rest and that the pads are withdrawn during the same reciprocation of the rod to permit unobstructed operation of the marking means. Following the marking of the blanks at the time resting on the bottoms 172, the latter operate to tip downwardly and discharge the blanks into the magazines below, all as above described.
- Secured in a bearing 260 at the rear end

of the machine is a shaft 262 on which are secured the loose and fast pulleys 264 and 266 with a belt shifter 268 connected by a rod 270 (Fig. 2) to a handle 272 at the front 5 of the machine in a position readily accessible to the operator and to be employed in starting and stopping the machine. As shown, at the front end of the shaft 262 is a gear 274 which meshes with a larger gear 10 276 on the shaft 278 which carries the barrel cam 146, there being provided a cam groove 280 for a collar at the lower end of a lever arm 282 fixed to the shaft 28 whereby the said shaft is given its rocking movement referred to a number of times in the foregoing description.

In the operation of the machine the operator stands at the front of the machine as shown in Fig. 5 of the drawings and introduces blanks as they come to hand from a stack or blank container. In other words, the blanks are not selected but are taken at random and placed one at a time upon the table 8 preferably in contact with the pins 25 10 extending upwardly from the slides 12. At regular intervals the slides 12 carry the blank into the machine within reach of the feed bars 40 with their feeding pawls 44, the timing of the feeding mechanisms being 30 such that the operator with very ordinary skill can attend to the machine and supply a blank for each reciprocation of feeding-in mechanism represented by the slides 12. After the machine has been in operation 35 for a short time a whole series of blanks will be passing over the trap doors 32 and during each cycle of the machine some of the blanks will be ejected through the operation of the trap doors in the manner above 40 described. As will be understood from the foregoing description the collection of the blanks in the different magazines, in accordance with the particular range of dimensions of the blanks for which the machine 45 has been set, is carried out automatically, together with a stamping operation to identify the blanks for each magazine, if such an operation is found to be necessary or 50 desirable.

Having described my invention, what I claim as new and desire to secure by Letters Patent of the United States is:—

1. In a machine of the character described, 55 a support for blanks, means for caliper-
ing the length dimensions of blanks as they pass along the support, and means operated by the calipered blanks for discharging the blanks from the support in accordance with the determinations of the caliper-
ing means, said caliper-
ing means being arranged to supply the pressure which enables the blanks to operate the discharging means.

2. In a machine of the character described, 55 a support for blanks, a plurality of caliper-
ing mechanisms simultaneously operative to

caliper a plurality of blanks along a length dimension of each, and means operated by the calipered blanks for discharging the blanks from the support at stations determined by the operations of the caliper-
ing means.

3. In a machine of the character described, a support for blanks, caliper-
ing means comprising a plurality of gages arranged in stepped relation in a series to contact with the edges of a plurality of blanks, means for simultaneously operating the gages, and means controlled by the gages and operated through the blanks for discharging blanks properly calipered at stations determined by the caliper-
ing means.

4. In a machine of the character described, a support for the blanks comprising trap doors over which the blanks are moved, latching means for the doors, and caliper-
ing means comprising a plurality of gages for contacting with the blanks and movable along the support, to control the latching means.

5. In a machine of the character described, means for assorting a plurality of blanks simultaneously in accordance with differences in a given dimension thereof, means for stamping on each blank an identifying mark, and means for depositing each blank in its appropriate delivery position.

6. In a machine of the character described, a support for the blanks, means for moving a plurality of blanks along the support, a plurality of gages, and means co-operating with the gages in caliper-
ing operations for effecting the discharge of the blanks as they pass along the support in accordance with differences in a length dimension of the blanks.

7. In a machine of the character described, a support for blanks, means for moving the blanks along the support, a plurality of gages of different lengths arranged in stepped relation in a series, a member arranged to carry the gages, and means co-operating with the gages in caliper-
ing operations for effecting the discharge of blanks from the support in accordance with differences in a length dimension of the blanks.

8. In a machine of the character described, a support along which blanks are movable, a plurality of trap doors in the support, a plurality of gages one opposite each trap door operative to gage the length of blanks, and means co-operating with a gage for releasing the corresponding trap door when a blank of the proper length has been gaged by one of the gages.

9. In a machine of the character described, a support for blanks comprising a plurality of trap doors over which the blanks are moved in a row, and a plurality of gages operative to test the blanks along

a length dimension and operative to control the trap doors so that the latter are opened to permit the proper blank to drop therethrough.

5 10. In a machine of the character described, a support along which the blanks are movable in a row, said support comprising a plurality of trap doors, means for moving the blanks from one trap door to another, gages for testing the blanks along a length dimension as they rest upon the doors, and means controlled by the gages for releasing the trap doors upon which blanks of the proper dimension have been 15 positioned.

11. In a machine of the character described, a support for blanks comprising a plurality of trap doors, a latch for each door, means for moving the blanks along 20 the support so that each in turn rests upon a trap door, and means for moving each blank toward a latch to test each blank along a given dimension, the construction and arrangement being such that the blank releases 25 the latch at the proper trap door whereby the blanks are distributed according to variations in the given dimension.

12. In a machine of the character described, a plurality of trap doors, means for 30 positioning blanks successively over the trap doors, a latch for each trap door, and a plurality of gages arranged to engage the blanks to push the latter toward the latches of the doors, the construction and arrangement being such that the gages together 35 with the latches measure the blanks along the given dimension so that when the latch is engaged by the proper blank it will be moved to release the trap door whereby 40 blanks are sorted in accordance with differences in the given dimension.

13. In a machine of the character described, a support for blanks comprising a plurality of trap doors, means for moving 45 the blanks progressively along the support and over the trap doors, gages for the blanks, and latches for the trap doors arranged to co-operate with the gages as caliper means for the blanks and operative to release the doors when a blank of the proper dimension becomes positioned on the door.

14. In a machine of the character described, a plurality of trap doors, means for 55 successively moving blanks over the doors, means for measuring the blanks along a given length dimension and for releasing the trap doors when a blank of the required dimension rests on a given door, and means 60 for automatically relatching the trap door in blank supporting position.

15. In a machine of the character described, a support comprising a plurality of trap doors, a latch for each door, means for 65 moving a row of blanks intermittently along

over the trap doors, and means for shoving the blanks along the support over toward the latches, the construction and arrangement being such that the doors are released when blanks of the required dimension are 70 shoved against the latches.

16. In a machine of the character described, a plurality of trap doors, a reciprocal member for moving a row of blanks along over the doors, latches for the 75 doors, a plurality of gages movable in a direction to shove the blanks against the latches, the construction and arrangement being such that blanks of the proper length operate the latches to release the trap doors. 80

17. In a machine of the character described, a support for a plurality of blanks, said support comprising trap doors on which the blanks may rest, latches for the doors, a plurality of gages, a member carrying said gages and movable to bring the gages in contact with the blanks to shove the latter toward the latches whereby the latches are released by certain of the blanks 85 which have the requisite length, and means 90 for simultaneously relatching those doors which have distributed blanks, the last mentioned operation taking place prior to another feeding operation on the blanks. 95

18. In a machine of the character described, means for selecting blanks in accordance with variations in a given dimension, stamps for placing identifying characters on the blanks in accordance with the determinations of the selecting means, a plurality of magazines occupying fixed locations, and means individual to each magazine for discharging the blanks into the proper magazines after the stamping operation. 100

19. In a machine of the character described, a support for blanks comprising a plurality of trap doors over which the blanks are moved at regular intervals, means controlled by the blanks for releasing the trap doors so as to drop the blanks at their proper delivery stations, a plurality of magazines related to the said stations to receive the blanks, and a second series of trap doors above the magazines 110 for receiving the blanks and for holding them temporarily while an operation is performed thereon previous to their being deposited in the magazines. 115

20. In a machine of the character described, a support along which blanks are fed, means comprising a series of trap doors for selecting the blanks in accordance with variations in the given characteristic of the blanks, magazines for receiving the blanks, and a second series of trap doors interposed between the first series and the magazines 125 for receiving the blanks and holding them while an operation is performed thereon. 130

21. In a machine of the character described, a support along which blanks are fed, and two series of trap doors one above the other for selecting the blanks in accordance with variations in a given characteristic thereof and for holding them temporarily during an operation thereon and for then permitting them to drop into the magazines provided for their reception.
22. In a machine of the character described, a support along which blanks are fed, means for sorting the blanks in accordance with differences in a given characteristic thereof and discharging them along different paths, and means located adjacent to each path for applying an identifying mark to each blank prior to its discharge at its proper station.
23. In a machine of the character described, a support along which blanks are fed, means for sorting the blanks in accordance with differences in a given characteristic thereof, means for stamping on each blank an identification mark, a plurality of magazines, and means for discharging the blanks to the magazines comprising plates which support the blanks during the stamping operations.
24. In a machine of the character described, means for sorting blanks in accordance with differences in a given characteristic thereof and depositing them in different compartments provided for the purpose of receiving the blanks, means associated with the different compartments for stamping identification marks on the blanks, and means for automatically discharging the blanks to their proper receiving stations.
25. In a machine of the character described, means for sorting blanks and depositing them in the various compartments provided therefor, said compartments comprising plates upon which the blanks are received, oscillatable means for stamping identification marks on the blanks resting on said plates, and means for operating the plates to discharge the blanks and to return them to blank supporting position.
26. In a machine of the character described, means for sorting blanks, a plurality of plates or supports for receiving the blanks from the sorting means, and means for stamping identification marks on the blanks resting on said plates, said last mentioned means comprising rotatable marking heads, and means for inking the same and operative to stamp the blanks while they rest on said plates.
27. In a machine of the character described, means for sorting blanks and depositing them in different compartments provided for the purpose, means for stamping identification marks on the blanks, means for supporting the blanks while they are thus marked, means for inking the stamping means, means operating to discharge the blanks after the stamping operation, and means comprising a single cam member for operating all of the first mentioned means.
28. In a machine of the character described, means for sorting blanks, a plurality of plates for receiving the blanks from the sorting means, means for marking the blanks as they rest on said plates, a plurality of magazines, and means for operating the plates to discharge the blanks to the magazines and to return them to blank supporting position, said marking means comprising stamping or marking heads movable into and out of the path of the blanks as they pass from the sorting means to the supporting plates.
29. In a machine of the character described, a support along which blanks may be moved, a plurality of trap doors for sorting the blanks as they move along the support, a second series of trap doors for receiving the blanks and supporting them during another operation thereon, and means for automatically operating both sets of trap doors.
30. In a machine of the character described, a support comprising a plurality of trap doors over which the blanks are moved, latches for the doors, blank controlled means for operating the latches to release the doors, said means comprising a pin to be engaged by one surface of the blank, and a gage to engage another surface of the blank, both pin and gage being adjustable so that the range of the given characteristic of the blank may be varied at the will of the operator.
31. A machine for stamping blanks in accordance with selected length dimensions of the blanks comprising a series of stamps each adapted to stamp a blank having a given length dimension, and means for delivering in operative position to each stamp only those blanks which correspond in length dimensions to the mark carried by that stamp.
32. In a machine of the character described, a support for blanks comprising a plurality of trap doors, a latch for each door, means for moving the blanks as they rest upon the trap doors to cause the blanks to release the latches at the proper trap doors whereby the blanks are discharged according to differences in a given dimension.
33. In a machine of the character described, a plurality of trap doors, a latch for each trap door, and a plurality of gages of different lengths arranged to engage the blanks to push the latter along the doors toward the latches of the doors, the construction and arrangement being such that the gages together with the latches measure the blanks along the given dimension so that when the latch is engaged

by the proper blank it will be moved to release the trap door whereby blanks are sorted in accordance with differences in the given dimension.

34. In a machine of the character described, a support for blanks comprising a plurality of trap doors, and means for moving the blanks along the support and into position above the doors comprising a reciprocable members having feed fingers spaced apart a distance corresponding substantially to the width of the doors.

35. In a machine of the class described, a support for blanks comprising a plurality of trap doors, and means for moving the blanks along the support and successively in position above the doors comprising a reciprocable member having feed fingers operable to engage an edge of the blanks successively to feed them into position above the doors and to move idly over the blanks in the reverse direction preliminary to each successive feeding movement.

36. In a machine of the class described, a support for blanks comprising a plurality

of trap doors, reciprocable members comprising feed fingers spaced apart a distance corresponding substantially to the width of the trap doors and operable to engage an edge of the blanks successively to feed them into position above the doors, latches for the doors, and a member movable transversely to the path of the reciprocated member for moving the blanks against the latches to cause unlatching of the doors when the proper blanks are resting thereon.

37. A machine for stamping identification marks on work pieces in accordance with a dimension of the work pieces comprising a series of stamps, a selecting mechanism for delivering to each stamp only those pieces having a dimension corresponding to the mark carried by that stamp, and operating means for causing all the stamps to act simultaneously upon the corresponding work pieces.

In testimony whereof I have signed my name to this specification.

WILLIAM C. STEWART.

by the proper blank it will be moved to release the trap door whereby blanks are sorted in accordance with differences in the given dimension.

- 5 34. In a machine of the character described, a support for blanks comprising a plurality of trap doors, and means for moving the blanks along the support and into position above the doors comprising a reciprocable members having feed fingers spaced apart a distance corresponding substantially to the width of the doors.
- 10 35. In a machine of the class described, a support for blanks comprising a plurality of trap doors, and means for moving the blanks along the support and successively in position above the doors comprising a reciprocable member having feed fingers operable to engage an edge of the blanks successively to feed them into position above the doors and to move idly over the blanks in the reverse direction preliminary to each successive feeding movement.
- 15 36. In a machine of the class described, a support for blanks comprising a plurality

of trap doors, reciprocable members comprising feed fingers spaced apart a distance corresponding substantially to the width of the trap doors and operable to engage an edge of the blanks successively to feed them into position above the doors, latches for the doors, and a member movable transversely to the path of the reciprocated member for moving the blanks against the latches to cause unlatching of the doors when the proper blanks are resting thereon.

37. A machine for stamping identification marks on work pieces in accordance with a dimension of the work pieces comprising a series of stamps, a selecting mechanism for delivering to each stamp only those pieces having a dimension corresponding to the mark carried by that stamp, and operating means for causing all the stamps to act simultaneously upon the corresponding work pieces.

In testimony whereof I have signed my name to this specification.

WILLIAM C. STEWART.

Certificate of Correction.

It is hereby certified that in Letters Patent No. 1,595,172, granted August 10, 1926, upon the application of William C. Stewart, of Swampscott, Massachusetts, for an improvement in "Sorting Machines," errors appear in the printed specification requiring correction as follows: Page 1, line 85, strike out the article "the"; page 6, lines 102 and 103, claim 18, for the misspelled word "magazing" read *magazine*; page 7, lines 111 and 112, claim 31, for "dimensions" read *dimension*; page 8, line 9, claim 34, strike out the article "a", and line 33, claim 36, for the word "reciprocated" read *reciprocable*; and that the said Letters Patent should be read with these corrections therein that the same may conform to the record of the case in the Patent Office.

Signed and sealed this 21st day of December, A. D. 1926.

[*SEAL*]

M. J. MOORE,
Acting Commissioner of Patents.
